UNITED STATES PATENT OFFICE.

THOMAS P. FORD AND THOMAS B. FORD, OF NEW YORK, N. Y.

AUTOMATIC REFILLING APPARATUS FOR PRESSURE-TANKS.

No. 909,574.

Specification of Letters Patent.

Patented Jan. 12, 1909.

Application filed October 12, 1907. Serial No. 397,099.

To all whom it may concern:

Be it known that we, THOMAS P. FORD and THOMAS B. FORD, citizens of the United States, and residents of the city of New York, borough of Brooklyn, in the county of Kings and State of New York, have invented a new and Improved Automatic Refilling Apparatus for Pressure-Tanks, of which the following is a full, clear, and exact description.

The invention relates to sprinkler systems for buildings, and its object is to provide a new and improved automatic refilling apparatus for pressure tanks, arranged to automatically keep the overhead water tank supplied with water, and to maintain a predetermined pressure on the water in the tank.

The invention consists of novel features and parts and combinations of the same, which will be more fully described herein-after and then pointed out in the claims.

A practical embodiment of the invention is represented in the accompanying drawings, forming a part of this specification, in which similar characters of reference indicate corresponding parts in both views.

Figure 1 is a side elevation of the improvement as applied, the building being shown in section and part of the water tank being shown broken out, and Fig. 2 is an enlarged sectional side elevation of the controlling device.

The overhead pressure tank A is preferably located on top of the building B, provided with a sprinkler system C of any approved construction, and supplied with water from the pressure tank A. Opposite the pressure tank A is located a controlling device D for automatically controlling the auxiliary supply of the water and air for the pressure tank A. As shown in Fig. 1, the pressure tank A is supplied with water from a water pump E, while an air pump F furnishes the air pressure for the pressure tank A, both pumps E and F being preferably located in the basement of the building B, and being provided with suitable pressure governors E' and F', to automatically start the pumps when the pressure in the discharge pipes E² and F² of the said pumps E and F falls below the pressures at which the governors E' and F' are set.

The controlling device D is provided with a closed casing D' connected at its bottom by a pipe G with the pressure tank A, so that the water rises and falls simultaneously in the tank A and the casing D'. In the casing D' is arranged a float H rising and falling with the water in the casing D', and the said float H is connected by its lever H' with the valve stem I, terminating at its ends in valves I' and I², of which the valve I' is normally seated in the seat J' of a valve-casing J opening into the casing D' and connected with the discharge pipe E² of the water pump E. The other valve I² is normally open, but is adapted to close a valve seat K' in a valve casing K attached to the casing D' at the outside thereof, the said valve-casing K being connected with the discharge pipe F² of the air pump F, and being connected by a pipe F³ with the upper portion of the pressure tank A, to supply the latter and the casing D' with air under pressure.

The discharge pipe E² is provided with a valve E³, and the said discharge pipe E² is connected at a point between the pump E and the said valve E³ by a branch pipe E⁴ with the pressure tank A, and in the said branch pipe E⁴ is arranged a valve E⁵ normally closed while the valve E³ is normally open. When it is desired to initially fill the pressure tank A with water, the valve E³ is closed and the valve E⁵ opened, and the pump E started, so that the latter pumps the water directly into the pressure tank A, to fill the same to the desired height indicated by the water gage L shown in Fig. 1. When the tank A is filled the water pump E is stopped and the valve E⁵ is closed, while the valve E³ is opened. When the pressure tank A is filled with water to the desired height, then the water level in the casing D' holds the float H in an uppermost position, to cause the valve I' to be seated on its seat J', thus disconnecting the water pump E from the casing D'. At the same time the valve I² is opened, so that the air pump F pumps air directly into the pressure tank A, to keep the water therein under the desired pressure, and when this pressure is reached the air pump F automatically stops owing to the action of the pressure governor F'. Now when the water

- in the pressure tank A leaks out of the same for whatever cause, and the water level consequently falls in the said tank A and in the casing D', then the float H moves downward, and in doing so shifts the valve stem I of the double valve I', I² in an upward direction, to move the valve I² into a closed position on its seat K', and to move the valve I' off its seat J'. When this takes place the connection between the air pump F and the pressure tank A is more or less shut off while the water pump E is connected with the casing D', and as the pressure on the pressure governor E' has decreased, it is evident that the water pump E starts and pumps water into the casing D', thus refilling the same and the pressure tank A, owing to the pipe G connecting the casing D' with the pressure tank A. The water in the tank A is replenished, and when the water has reached the desired level in both the tank A and the casing D' then the float H has risen sufficiently to again shift the double valve I', I², to move the former to its seat J' and the valve I² off its seat K'. Thus the water pump E is again disconnected from the casing D' and comes to a stop while the air pump F is again connected with the pressure tank A, to supply the latter with the desired air pressure. From the foregoing it will be seen that whenever there is any leakage however small, in the pressure tank A, the water pump E is automatically started to supply the deficiency of water in the tank A, and during this time the air pressure is shut off from both the pressure tank A and the casing D', to allow of refilling the same to the desired level.
- From the foregoing it will be seen that the pressure tank A is at all times charged with the proper amount of water, subjected to air pressure, so that the sprinkler system is kept in a high state of efficiency.
- Although the improvement is more particularly shown and described for use with pressure tanks employed in sprinkler systems, it is evident that it may be used on pressure tanks utilized for other purposes.
- Having thus described our invention, we claim as new and desire to secure by Letters Patent:
1. An automatic refilling apparatus for pressure tanks, comprising a pressure tank, a water pump for filling the pressure tank, an air pump independent of the said water pump for maintaining air pressure on the water in the said tank, and a controlling device governed by the rise and fall of the water in the said pressure tank and controlling the said air pump and the said water pump.
  2. An automatic refilling apparatus for pressure tanks, comprising a pressure tank,
- an air pump having a pressure governor, a water pump having a pressure governor, and a controlling device connected with the said pressure tank, and having a valve mechanism controlled by the rise and fall of the water in the said pressure tank, the said valve mechanism governing a normally open connection between the air pressure side of the said pressure tank and the air pump, and a normally closed connection between the water pump and the controlling device, to automatically open the water pump connection and to close the air pump connection when the level of the water falls in the pressure tank.
3. An automatic refilling apparatus for pressure tanks, comprising a pressure tank, an air pump having a pressure governor, a water pump having a pressure governor, a connection between the water pump and the pressure tank, a controlling device set opposite the said pressure tank and having a valve mechanism and a casing, a connection between the casing and the pressure tank for the water to rise and fall simultaneously in both the pressure tank and the casing, and a connection between the casing and the water pump, the said valve mechanism having a float rising and falling with the water in the said casing, and a valve controlled by the float and controlling the said connection between the air pump and the pressure tank and the said connection between the said casing and the water pump.
4. An automatic refilling apparatus for pressure tanks, provided with a controlling device for automatically controlling the water supply and the air supply for the said pressure tank, the said controlling device having a casing connected with the pressure tank for the water to rise and fall simultaneously in both the pressure tank and the casing, a float in the casing and rising and falling with the water therein, and a double valve controlled by the said float and controlling the air pressure connection and the water supply connection to the said pressure tank.
5. An automatic refilling apparatus for pressure tanks, comprising a pressure tank, an air pump having a pressure governor, a water pump having a pressure governor, a connection between the water pump and the pressure tank, a controlling device set opposite the said pressure tank and having a valve mechanism and a casing, a connection between the casing and the pressure tank for the water to rise and fall simultaneously in both the pressure tank and the casing, a connection between the casing and the water pump, the said valve mechanism having a float rising and falling with the water in the said casing and a valve controlled by the float and controlling the said connection be-

tween the air pump and the pressure tank and the said connection between the said casing and the water pump, and a valved branch connection leading from the said connection between the water pump and the casing to the pressure tank.

In testimony whereof we have signed our

names to this specification in the presence of two subscribing witnesses.
